UNITED STATES PATENT OFFICE.

CHARLES T. HENNIG, OF BROOKLYN, NEW YORK.

DESIGN FOR A HAMMER.

SPECIFICATION forming part of Design No. 35,100, dated September 17, 1901.

Application filed August 6, 1901. Serial No. 71,112. Term of patent 3½ years.

To all whom it may concern:

Be it known that I, CHARLES T. HENNIG, a citizen of the United States, residing at Brooklyn, in the county of Kings and State of New York, have invented and produced a new and original Design for a Hammer, of which the following is a specification, reference being had to the accompanying drawings, forming part thereof.

Figure 1 is a side view of my hammer, and Fig. 2 is an end view of the head of the same. As shown in the drawings, the leading or material feature of my design consists of a hammer having the head A flattened at one end to form a striking-surface, as at C, and tapering to an edge at the other end, as at D, and the handle B having projecting annular ribs or collars 1 and 2 thereon. A projection

3 extends from the front of the head approximately in line with the handle. The sides of the handle and head are ornamented with relief-work, as shown. The front and rear of the head are left smooth, as shown.

Having described my invention, what I claim as new, and desire to secure by Letters Patent, is—

The design for a hammer, as herein shown and described.

In testimony whereof I have signed my name to this specification in the presence of two subscribing witnesses.

CHARLES T. HENNIG.

Witnesses:

H. M. SEAMANS,
I. V. SCOTT.
